ELECTRIC KNIFE HANDLE

Isadore Leyden, Shrub Oak, N.Y., assignor to Riviera Appliance Corp., Brooklyn, N.Y., a corporation of New York

Filed July 5, 1963, Ser. No. 75,676

Term of patent 14 years

(Cl. D22—3)

FIG. 1

FIG. 2

FIG. 3

FIG. 4

FIG. 5

FIGURE 1 is a side elevational view of an electric knife handle showing my new design;

FIGURE 2 is a top plan view thereof;

FIGURE 3 is a bottom view thereof;

FIGURE 4 is an end view as seen from the right; and FIGURE 5 is an end view as seen from the left.

I claim:

The ornamental design for an electric knife handle, substantially as shown.
